UNITED STATES PATENT OFFICE.

WILLIAM E. JAQUES, OF GRAND RAPIDS, MICHIGAN, ASSIGNOR TO ALFRED O. CROZIER, OF GRAND RAPIDS, MICHIGAN.

RAIL-SUPPORT.

SPECIFICATION forming part of Letters Patent No. 723,280, dated March 24, 1903.

Application filed May 13, 1902. Serial No. 107,184. (No model.)

To all whom it may concern:

Be it known that I, WILLIAM E. JAQUES, a citizen of the United States of America, residing at Grand Rapids, in the county of Kent and State of Michigan, have invented certain new and useful Improvements in Rail-Supports; and I hereby declare the following to be a full, clear, and exact description of the invention, such as will enable others skilled in the art to which it pertains to make and use the same.

This invention relates to improvements in rail-supports, and pertains more especially to improved means for fastening the rails of a railway-track to ties of cement or artificial stone.

One object of this invention is to hold the rails of a railway-track in place upon the ties supporting them, which invention is simple and durable in construction and readily applied.

Another object is to provide meritorious means whereby the rails are rendered adjustable laterally to a limited extent in the one or the other direction.

With these objects in view and to the end of realizing other advantages hereinafter appearing my invention consists in certain features of construction and combinations of parts hereinafter described, and pointed out in the claims.

In the accompanying drawings, Figure I is a vertical section showing the two rails of a railway-track secured in place by means embodying my invention. Fig. II is a top plan in section on line II II, Fig. I.

Portions are broken away in the drawings to reduce the size of the drawings.

Referring to the drawings, *a* designates a tie which is instrumental in supporting the rails *b* of a railway-track. The tie *a* is arranged in the usual manner below and transversely of the rails. The tie *a* consists, preferably, of a block of cement or artificial stone.

Each rail *b* is not seated directly upon the tie, but rests upon the upper side of a plate *d*, interposed between the base of the rail and the tie, which plate is preferably a metal plate fixed to the tie, as will hereinafter appear. The said plate *d* is preferably sunk 50 into the tie, as shown in Fig. I.

Each plate *d* is secured to the tie by a bolt *e* and a coöperating nut *f*, and the said plate is provided below the base of the rail upon it with an upwardly-flaring bolt-hole *g*, which is occupied by the upwardly-flaring head *h* of the bolt *e*. The externally-screw-threaded shank of the said bolt extends downwardly through the tie, and the coöperating correspondingly screw-threaded nut *f* is mounted upon the lower end of the shank within a recess *k*, formed in the under side of the tie. The head of the bolt has its upper surface flush with the upper surface of the plate *d*.

Between each plate *d* and the base of the rail upon the said plate is shown a sheet *l*, of rubber or other elastic material, capable of somewhat cushioning the base of the rail and extending over the head of the bolt, and thereby positively preventing contact between the under side of the rail-base and the said head.

Each plate *d* at and a short distance from the outer side of the rail upon the said plate is bent or flanged upwardly, as at *m*, and the said flange *m* overhangs a wedge *n*, which is driven between the inner side of the said flange and the outer edge of the base of the rail. The wedge *n* engages the outer edge of the rail and preferably overhangs and tightly engages the upper side of the rail-base at the outer side of the rail and is instrumental in holding the rail down upon the said plate *d*. The said flange *m* overhangs the said wedge *n* and is therefore instrumental in holding the said wedge down upon the said plate *d*, and the said wedge and the said wedge-overhanging flange constitute a stop preventing outward lateral displacement of the said rail upon the said plate.

Each plate *d* at and a short distance from the inner side of the rail is bent or flanged upwardly, as at *o*, and the said flange *o* overhangs a wedge *r*, which is driven between the inner side of the said flange *o* and the inner edge of the base of the said rail. The wedge *r* engages the inner edge of the said rail and preferably overhangs and engages the upper side of the said rail-base at the inner side of the rail and is consequently instrumental in holding the rail down upon the said plate *d*.

The said flange *o* preferably overhangs the said wedge *r*, and thereby holds the said wedge down upon the said plate *d*. The said wedge *r* and the said flange *o* form a stop 5 preventing inward lateral displacement of the said rail upon the said plate.

Obviously the two wedges *n* and *r* upon each plate *d* are not only instrumental in holding the engaging rail in place upon the 10 said plate *d*, but render the said rail capable of a limited adjustment laterally upon the said plate, and the said rail is slightly shifted laterally in the one direction or the other by a proper manipulation of the said wedges. 15 For instance, the driving or forward actuation of a wedge *n* when the opposite wedge *r* has been backed up results in slightly shifting the engaging rail upon the plate *d* laterally and inwardly, whereas the driving or forward 20 actuation of the said wedge *r* when the said wedge *n* is backed up results in crowding the rail laterally and outwardly upon the said plate.

A tie-bar *t* is instrumental in tying the two 25 rails of the railway-track together. The bar *t* is embedded within and extends longitudinally of the tie, preferably centrally between the top and bottom of the tie. The bar *t* extends below the plates *d* under both rails. 30 The bar *t* is perforated, as at *s*, to accommodate the location of the bolts *e*. The bar *t* at the outer side of each rail is provided with an upwardly-projecting arm *u*, which extends upwardly above the tie and engages the plate *d* at the outer side of the outer flange *m* of the 35 said plate and preferably somewhat snugly overhangs the said flange *m*, as at *x*, and affords an outer bearing or brace for the said flange.

40 By the construction hereinbefore described it will be observed that the plates *d* under both rails are positively prevented from displacement longitudinally of the tie by the tie-bar *t*, and the said bar having members overhanging the outer flanges *m* of the plates *d* is instrumental also in holding the said plates down upon the tie.

It will be observed that the flanges *m* and *o* of each plate *d* form abutments arranged 50 at opposite sides, respectively, of and a suitable distance from the rail, which extends over and across the said plate, and limit lateral adjustment of the said rail in opposite directions, respectively, and endwise-shiftable 55 wedges are interposed between the said abutments and the said rail. Hence each rail of the railway-track by actuating the wedges which are arranged at opposite sides, respectively, of the said rail, so as to drive or tighten the 60 wedge at one side of the rail and partially withdraw the wedge at the opposite side of the rail is readily and accurately readjusted relative to the other rail.

What I claim is—

65 1. The combination, with the two rails of a railway-track, the tie arranged below and transversely of the rails, plates interposed be-

tween the tie and the rails, means instrumental in holding the rails in place upon the said plates, and means instrumental in fastening 70 the said plates to the tie, of a tie-bar embedded within and extending longitudinally of the tie and having upwardly-projecting arms extending upwardly at the outer sides of the rails and arranged to tie the aforesaid 75 plates together.

2. The combination, with the two rails of a railway-track, the tie arranged below and transversely of the rail, plates interposed between the tie and the rails and having upwardly-projecting flanges at the outer sides of the rails, means for holding the rails in place upon the plates, and means instrumental in fastening the said plates underneath 85 the rails to the tie, of a tie-bar embedded within and extending longitudinally of the tie and having members engaging the outer sides of the aforesaid flanges.

3. The combination, with the two rails of a railway-track, the tie arranged below and 90 transversely of the rails, plates interposed between the tie and the rails and having upwardly-projecting flanges at the outer sides of the rails, and means instrumental in holding the rails in place upon the plates, of a 95 tie-bar extending longitudinally of the tie and having upwardly-projecting arms engaging the outer sides of and overhanging the said flanges.

4. The combination, with the two rails of a 100 railway-track; a tie arranged below and transversely of the rails; plates interposed between the tie and the rails, means instrumental in holding the rails in place upon the said plates, and means instrumental in fastening the said 105 plates to the tie, of a tie-bar arranged within and extending longitudinally of the tie, which bar has an upwardly-projecting arm extending upwardly above the lower surface of the base of the rails into engagement with and arranged to prevent displacement of one of the aforesaid plates longitudinally of the tie in one direction, and is provided with another upwardly-projecting arm extending upwardly above the said surface of the base of 110 the rails into engagement with and arranged to prevent displacement of the other of the aforesaid plates longitudinally of the tie in the opposite direction.

5. The combination, with the two rails of a 115 railway-track, and a tie arranged below and transversely of the rails, of plates interposed between the rails and the tie and having upwardly-projecting flanges at the sides of the rails, wedges interposed between the said 120 flanges and the rails, and a tie-bar having members engaging the outer sides of the outer flanges of the plates.

6. The combination, with the two rails of a 125 railway-track, and a tie arranged below and transversely of the rail, of plates interposed between the rails and the tie, means for adjusting the rails laterally and securing them in the desired adjustment, and a tie-bar em-

bedded within and extending longitudinally of the tie and having arms extending upwardly at the outer sides of the rails and arranged to prevent displacement of the aforementioned plates outwardly from each other.

5 In testimony whereof I sign the foregoing specification, in the presence of two witnesses,

this 12th day of April, 1902, at Cleveland, Ohio.

WILLIAM E. JAQUES.
